CURRENT RESPONSIVE DEVICE

Theodore A. Rich, Schenectady, N. Y., assignor
to General Electric Company, a corporation of
New York

Application October 22, 1936, Serial No. 107,002

6 Claims. (Cl. 171—95)

My invention relates to current-responsive devices and concerns particularly deflecting instruments.

It is an object of my invention to provide an instrument having an especially light weight armature with a high ratio of torque to weight in order to obtain a quick response.

It is also an object of my invention to provide an instrument of simplified construction which may be produced at relatively low cost.

Still another object of my invention is to provide a long-scale instrument.

Other and further objects and advantages will become apparent as the description proceeds.

In carrying out my invention in its preferred form, I provide a field structure with a pair of annular pole pieces and a shaft extending through said pole pieces. A flat spiral of current-conducting material attached at the inner end to the shaft and at the outer end to the stationary portion of the apparatus is mounted on the shaft between the pole pieces and is provided with current connections. The arrangement is such that radial force produced on the current-conducting spiral by the reaction between the current and the magnetic flux tends to wind or unwind the spiral, thus producing rotation of the shaft.

My invention may be understood more readily from the following detailed description when considered in connection with the accompanying drawings and the features of my invention which are believed to be novel and patentable will be pointed out in the claims appended hereto. In the drawings, Fig. 1 represents schematically in elevation one embodiment of my invention employing a single current-conducting spiral; Fig. 2 is a plan view of the arrangement disclosed in Fig. 1; Fig. 3 is a diagram illustrating the principle of operation of the invention; Fig. 4 is a plan view of a modified form of my invention in which one of the pole pieces is split to provide two air gaps and accommodate two current-conducting spirals; Fig. 5 is an elevation of the arrangement of Fig. 4; Fig. 6 is a fragmentary sectional view of the arrangement of Fig. 5 cut by a plane 6—6 passing through the axis of the armature of the instrument; Fig. 7 shows a modification of the arrangement of Figs. 4, 5, and 6 illustrating the application of my invention to wattmeters or to alternating-current circuits; Fig. 8 is an elevation of a modified arrangement in which no magnet is required; and Fig. 9 is a view of a section cut through the apparatus of Fig. 8 by a plane 9—9. Like reference char-

acters are utilized throughout the drawings to designate like parts.

Referring more in detail to Figs. 1 and 2, the stationary portion of the apparatus includes the field structure consisting of a permanent magnet 11 with annular pole pieces 12 and 13, a scale 14, and bearings, not shown. The annular pole pieces 12 and 13 are substantially similar, substantially coaxial, and axially spaced to provide an air gap 15 between them.

The movable portion of the apparatus comprises a rotatable shaft 16, the current-conducting spiral 17 within the air gap 15, and a pointer 18 carried by the shaft 16 to cooperate with the scale 14. The shaft 16 passes through the openings in the annular pole pieces 12 and 13 substantially coaxial therewith and the current-conducting spiral 17 is attached at the inner end to the shaft 16 and at the outer end to an insulated pin 19 attached to one of the pole pieces 13 or attached at some other suitable position to the stationary portion of the apparatus. The pin 19 forms one of the current-conducting terminals of the apparatus and the other terminal 20 may be connected to the shaft 16 in any suitable manner, as e. g., by means of a substantially torsionless current-conducting spiral in the manner usual to current-responsive instruments of the d'Arsonval type.

If desired, suitable damping means may be provided, such as a damping vane 21 of current-conducting material mounted on an arm 22 carried by the shaft 16. The damping vane 21 is in close proximity to the inner cylindrical surface 23 (Fig. 2) of the pole piece 12. The eddy currents induced in the damping vane 21 provide an effective means for bringing the movable element to a stop and preventing vibration thereof.

It is evident that the magnet 11 produces magnetic flux passing axially across the air gap 15 between the pole pieces 12 and 13. The current flowing through the spiral 17 passes perpendicularly to the lines of flux and, consequently, as shown in Fig. 3, the reaction between the flux and the current produces forces acting on the spiral ligament 17 perpendicular to the successive portions of the ligament 17 and also perpendicular to the shaft 16. Accordingly, each part of the ligament 17 is subjected to a force acting in the plane of the ligament 17 through the center of the spiral formed by the ligament 17. Depending upon the direction of current and the polarity of the pole pieces, the forces will be either outward or inward. In case the current

55

direction is such that the forces are radially inward, as illustrated by the arrows in Fig. 3, the spiral ligament 17 will tend to wind up, thus rotating the shaft 16. In the case of a spiral 5 wound as shown, the shaft will be rotated in the clockwise direction. On the other hand, in the case of reversal in the direction of current or reversal in polarization of the magnet 11, the spiral 17 will tend to unwind and rotate the shaft 10 16 in the opposite direction. For reasons later 15 to be explained, the former arrangement may give greater sensitivity.

It is apparent that the angle of deflection of the shaft 16 is not limited to a fraction of 360 15 degrees but that a very long scale instrument may be produced. In fact, if a suitable overhanging bearing support is provided which will not be struck by the pointer 18, the shaft 16 may be caused to rotate through a plurality of revolutions. 20 If desired, a separate biasing spring or other suitable biasing means may be provided for maintaining the pointer 18 in a predetermined zero position. However, it is apparent that such a biasing means is unnecessary in my construction 25 for the reason that the current-conducting spiral 17 itself serves as a biasing spring and, in the case of center-zero instruments, serves to bias the pointer to a position in the center of the scale.

30 In connection with Figs. 1 and 2, it was mentioned that the current connection between the terminal 20 and the shaft 16 might take the form of a current-conducting spiral or hairspring. For the sake of obtaining increased torque and for 35 effective utilization of material, such a second current-conducting spiral may be arranged in a second air gap, as shown in Figs. 4, 5 and 6. In the arrangement of Figs. 4, 5, and 6, the pole pieces are interleaved. One of the pole pieces 40 is forked or split into two parts, 24 and 25, each of which is annular and is spaced axially from an annular pole piece 26 in order to form a pair of air gaps 27 and 28. A pair of current-conducting spirals 29 and 30 are provided in the air 45 gaps 27 and 28, respectively, and each of the current-conducting spirals 29 and 30 has its inner end attached to the shaft 16 or to a current conductor carried thereby and the outer ends of the current-conducting spirals 29 and 30 are 50 electrically connected to binding posts 31 and 32, respectively, serving as the terminals of the instrument. The binding posts 31 and 32 are supported by the field structure but insulated therefrom. The torque produced by the two spirals 55 is in the same direction on 16.

60 Preferably, the current-conducting spiral ligaments 17 or 29 and 30 are composed of a material which combines the properties of high current conductivity and high flexibility. I have found certain copper alloys to be suitable for this purpose. For example, an alloy of 2.6% cobalt, 97% copper, and 0.4% beryllium may be employed. The ligaments may be in the form of thin strips in order to be sufficiently rigid to 65 maintain the proper position axially in the air gap and still offer very little resistance to bending. The exact thickness will, of course, be determined by the current to be carried and the desired full-scale reading of the instrument, 70 which in turn determines the amount of control torque desired for calibration purposes.

75 In the arrangement of Figs. 4, 5, and 6, the shaft 16 is mounted between cupped jewels carried in the ends of jewel screws 33 and 34, re-

spectively. The jewel screws 33 and 34 are mounted in suitable brackets 35 and 36, respectively.

In the embodiments of my invention shown in Figs. 1 and 4, a permanent magnet is shown for providing the magnetic field but it will be understood that my invention is not limited to this specific arrangement and that an electromagnet may also be employed for providing the magnetic field. In this case, the winding energizing 10 the electromagnet may be connected in series with the armature so as to form an instrument having a modified relationship between current and deflection. Such an instrument may also be employed for alternating currents, in which 15 case, the field structure is preferably partially laminated.

In Fig. 7, I have shown one manner of utilizing an electromagnet in connection with my invention for providing a magnetic field. The arrangement of Fig. 7 is connected for use as a wattmeter. It will be seen that the pole pieces 12 and 13 are attached to a yoke 37 upon which is wound a field coil 38. The coil 38 is connected in series with the electrical circuit 39 and the armature of the instrument is connected across the circuit 39 through a resistor 40. The field coil 38 accordingly serves as a current winding and the spiral ligaments 29 and 30 serve as a potential winding of an instrument in which a 30 torque is produced varying with the product of the instantaneous values of current and voltage. For use in alternating-current circuits, the yoke 37 is preferably laminated and the pole pieces 12 35 and 13 may also be partially laminated.

It will be understood that my invention is not limited to the use of any particular form of damping mechanism. For example, in the arrangement of Figs. 5 and 6, the damping element takes the form of a disk 41 carried by the shaft 40 16 in one of the air gaps and, as the shaft 16 rotates, it causes the disk 41 to cut the magnetic flux, inducing eddy currents, the reaction of which produces the well known form of damping 45 action.

In the arrangement of Fig. 7, the damping element takes the form of a closed loop 42 carried by the shaft 16 in such a manner as to link one of the annular pole portions 24. It will be apparent that damping current will be induced in 50 the loop 42 as this loop cuts the magnetic flux during rotation of the movable element.

When the directional characteristic or zero-center scale is desired, the arrangement will ordinarily be such that the flux produced by the 55 permanent magnet 11 or the solenoid winding 38 is relatively large compared with the flux produced by the current flowing in the current-conducting spiral 17. When such a directional effect is not desired, this consideration need not 60 be had but the arrangement will preferably be such that the current-conducting spiral 17 tends to wind up rather than unwind as the current therein increases. It is evident that, in adjacent turns of the spiral 17, current is flowing in the same direction and the reaction between such currents is such as to tend to draw the successive turns together. The resultant effect of the reaction between the current in successive turns of the spiral thus tends to close or wind the spiral quite independently of any magnetic flux which may be produced by a field structure. Consequently, the torque produced by reaction 70 between the currents in successive turns of the 75

spiral may be caused to aid the torque produced by the reaction between the current in the spiral and the flux produced by the field structure, and the sensitivity may be increased if the arrangement is such that the reaction between the current in the spiral and the flux produced by the field structure tends to wind up the spiral 17.

When it is desired to produce zero-center instruments having different sensitivities in one direction or the other, the characteristic just described may be made use of and the design may be such as to bring about a relationship between field flux and current which causes the reaction between the current in adjacent turns 15 to suppress the scale for one direction of deflection and to expand the scale of the instrument for the other direction of deflection.

A modified arrangement is disclosed in Figs. 8 and 9 in which the reaction between the currents flowing in successive turns of the spiral 17 is relied on for producing the turning moment of the armature of the instrument. Preferably, but not necessarily, a pair of current-conducting spirals 29 and 30 is employed and 25 is mounted in the manner already described on a shaft 16 and terminals 31 and 32 and occupies air gaps 26 and 27. The field structure, however, is preferably composed entirely of soft iron or some other suitable highly permeable 30 magnetic material and consists of a block of soft iron 43 with the slots 26 and 27 cut therein to form air gaps. Suitable openings are drilled therein to receive the shaft 16. The soft iron field structure 43 serves to increase the sensitivity of the instrument by reducing the magnetic reluctance of the space surrounding the current-conducting spirals 29 and 30, respectively. It will be apparent that the instrument illustrated in Figs. 8 and 9 is a universal instrument and may be employed for measuring either alternating or direct currents. The pointer 18 will tend to move in the direction corresponding to winding up the spirals 29 and 30, irrespective of the direction of current flow.

I have herein shown and particularly described certain embodiments of my invention and certain methods of operation embraced therein for the purpose of explaining its principle and showing its application, but it will be obvious to those skilled in the art that many modifications and variations are possible and I aim, therefore, to cover all such modifications and variations as fall within the scope of my invention which is defined in the appended claims.

What I claim as new and desire to secure by Letters Patent of the United States is:

1. A current-responsive device comprising in combination, a field structure having a pair of pole pieces, a relatively rotatable member, and a pair of current-conducting spirals, one of said pole pieces having substantially parallel pole faces on either side thereof and the other of said pole pieces being forked, the inner surfaces of the forked portion being substantially parallel to form pole faces, said first pole piece and said forked pole piece being interleaved with their pole faces substantially parallel and spaced to form a pair of air gaps, said current-conducting spirals each being mounted in one of said air gaps substantially parallel to said pole faces, the outer ends of said current-conducting spiral being mechanically connected to said field structure and electrically insulated therefrom and the inner ends of said current-conducting spirals being mechanically and electrically connected to

the rotatable element, the latter element having an axis of rotation substantially perpendicular to said pole faces.

2. A current-responsive instrument comprising in combination a field structure having a pair of annular pole pieces substantially coaxial and axially spaced to form an air gap therebetween, a flat current-conducting spiral within said air gap substantially perpendicular to the axis of said annular pole pieces, a rotatable shaft substantially coaxial with said pole pieces, and a damping loop carried by said shaft and linking one of said annular pole pieces, said loop forming a closed electrical circuit, the inner end of said current-conducting spiral being attached to said shaft and the outer end thereof being fixed in a stationary position.

3. A current-responsive instrument comprising in combination, a field structure having a pair of pole pieces with substantially parallel confronting pole faces spaced to form an air gap therebetween, a flat current-conducting spiral mounted in said air gap substantially parallel to said pole pieces, a rotatable member mounted with its axis of rotation substantially perpendicular to said pole faces, and a damping member of current-conducting material mounted on said rotatable member and intersecting the path of lines of flux between said pole faces, the inner end of said current-conducting spiral being attached to said rotatable member and the outer end being fixed in a stationary position.

4. A current-responsive wattmeter for an electrical circuit comprising in combination, a stationary member including a magnetic field structure of magnetizable material having a pair of pole pieces with substantially parallel confronting pole faces spaced to form an air gap therebetween and a current-conducting winding in inductive relation with said magnetizable field structure, a flat current-conducting spiral mounted in said air gap substantially parallel to said pole faces, and a rotatable member with an axis of rotation substantially perpendicular to said pole faces, the inner end of said current-conducting spiral being attached to one of said members and the outer end being attached to the other of said relatively rotatable members, said field winding and said current-conducting spiral each being connected to the electrical circuit in which watts are to be measured, one being connected in responsive relation to the current in said circuit to serve as a current winding and the other being connected in responsive relation to the voltage across said circuit to serve as a potential winding.

5. A zero-center current-responsive device with unequal scale distributions on either side of the zero point comprising in combination, a pair of relatively rotatable members and a current-conducting spiral, said spiral being connected at the inner end to one of said members and at the outer end to the other of said members, one of said members including a magnet having a pair of pole pieces with confronting substantially parallel pole faces spaced to form an air gap therebetween, the axis of relative rotation of said members being substantially perpendicular to said pole faces, said current-conducting spiral being mounted in said air gap, the strength of the magnet being such that appreciable winding torque is produced by the reaction between the current in the turns of the spiral relative to unwinding or winding torque which is produced by the reaction between the current in the spiral and the flux produced by the magnet.

6. A current-responsive device comprising in combination, a pair of relatively rotatable members and a current-conducting spiral, said spiral being connected at the inner end to one of said members and at the outer end to the other of said members, one of said members comprising magnetizable material formed into a structure having

substantially parallel confronting surfaces spaced to form an air gap therebetween, the axis of relative rotation of said members being substantially perpendicular to said confronting surfaces and said current-conducting spiral occupying said air gap.

THEODORE A. RICH.
